CLAIM

The ornamental design for an oil plate remover, as shown and described.

DESCRIPTION

FIG. 1 is a top plan view of the oil plate remover showing the new design;

FIG. 2 is a front plan view thereof, the opposite side being a mirror image;

FIG. 3 is a side elevation view thereof, the opposite side being a mirror image;

FIG. 4 is a perspective view thereof;

FIG. 5 is a bottom plan view;

FIG. 6 is an alternate perspective view of the oil plate remover, an oil plate being shown therein in dot-dash lines for illustrative purposes only.

FIG. 1

FIG. 2

FIG. 3

FIG. 4

FIG. 5

FIG. 6
